(57) **CLAIM**

The ornamental design for a component for a spray suppression device for a vehicle, as shown and described.

DESCRIPTION

FIG. 1 is a perspective view of a component for a spray suppression device for a vehicle showing my new design, wherein the separation and bracket are used to indicate no particular height of the component;

FIG. 2 is a perspective view of the component for a spray suppression device for a vehicle from another angle thereof, wherein the separation and bracket are used to indicate no particular height of the component; and,

FIG. 3 is an end view of the component for a spray suppression device for a vehicle shown in FIGS. 1 and 2.

1 Claim, 1 Drawing Sheet

FIG. 1

FIG. 2

FIG. 3
